Harold V. Saffell, Los Angeles, Calif.

Application August 29, 1944, Serial No. 115,110

Term of patent 3½ years

(Cl. D62—2)

To all whom it may concern:

Be it known that I, Harold V. Saffell, a citizen of the United States, a resident of Los Angeles, in the county of Los Angeles, State of California, have invented a new, original, and ornamental Design for a Spray Pump, of which the following is a specification, reference being had to the accompanying drawing, forming part thereof.

Fig. 1 is a top plan view of a spray pump embodying my new design;

Fig. 2 is a side elevation of same;

Fig. 3 is an elevation in a plane at right angles to Fig. 2.

I claim:

The ornamental design for a spray pump, as shown.

HAROLD V. SAFFELL.
